(57) **CLAIM**

The ornamental design for a glass solar panel, as shown and described.

DESCRIPTION

FIG. 1 is a front view of a glass solar panel;

FIG. 2 is a perspective view thereof;

FIG. 3 is a front view of another embodiment of a glass solar panel;

FIG. 4 is a perspective view thereof;

FIG. 5 is a front view of another embodiment of a glass solar panel;

FIG. 6 is a perspective view thereof;

FIG. 7 is a front view of another embodiment of a glass solar panel;

FIG. 8 is a perspective view thereof;

FIG. 9 is a front view of another embodiment of a glass solar panel;

FIG. 10 is a perspective view thereof;

FIG. 11 is a front view of another embodiment of a glass solar panel; and,

FIG. 12 is a perspective view thereof.

The design relates to a glass panel that incorporates an inset solar cell around its border.

The glass solar panel is shown with symbolic breaks, formed by broken lines. The appearance of any portion of the article between the break lines forms no part of the claimed design.
